Primary Examiner — Amber R Stiles*Assistant Examiner* — Karen M. Jones(74) *Attorney, Agent, or Firm* — Tommy S F Wang;
Wang IP Law Group, P.C.(57) **CLAIM**

The ornamental design for a lighter as shown and described.

DESCRIPTION

FIG. 1 is a perspective view of a lighter showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken line portions of the lighter in FIGS. 1-8 represent unclaimed portions of the lighter and form no part of the claimed design.

1 Claim, 7 Drawing Sheets(56)
